UNITED STATES PATENT OFFICE.

BYRON B. BOWER, OF BAINBRIDGE, GEORGIA.

AIR-PUMPING APPARATUS.

SPECIFICATION forming part of Letters Patent No. 721,662, dated March 3, 1903.

Application filed August 21, 1900. Serial No. 27,607. (No model.)

To all whom it may concern:

Be it known that I, BYRON B. BOWER, a citizen of the United States, residing at Bainbridge, in the county of Decatur and State of Georgia, have invented certain new and useful Improvements in Air-Pumping Apparatus, of which the following is a specification.

The general object of this invention is to provide improved apparatus for pumping air either for the purpose of compressing it or for exhausting it from a receptacle or for both compressing and exhausting it.

The special object of my invention is to so construct such apparatus that it may be operated at high speed while handling large volumes of air.

In carrying out my invention I provide a casing divided into chambers for the reception and for the discharge of air, said casing having centrally arranged within it a cylinder open at opposite ends acting as a guide for a combined cylinder and valve within which a piston moves and which is itself movable endwise to control the passage of air from the reception-chamber to the delivery-chamber of the casing. The cylinder acts as a valve and is moved at each stroke of the piston, and other automatic valves are employed coacting with the cylindrical valve to regulate the passage of air from one chamber to another. I provide also an additional valve-casing having valve mechanism so arranged that the apparatus may be reversed, what was in the first case the supply-pipe becoming the discharge-pipe, and vice versa. Said reversing mechanism may be actuated periodically or at long intervals to reverse the action of the pump, or the pump may be used without said reversing mechanism.

The details of construction are hereinafter fully described and the subject-matter deemed novel set forth in the claims.

In the accompanying drawings, Figure 1 shows a front elevation of my improved air-pumping apparatus, only so much of the mechanism employed being shown as is necessary to illustrate my invention. Fig. 2 is a view on an enlarged scale, showing a central longitudinal section of the apparatus. Fig. 3 is an elevation showing details of the mechanism

for actuating the endwise-movable cylinder and also details of the mechanism employed for actuating the reversing-valve. Fig. 4 shows a transverse section of the apparatus. Fig. 5 is a view, partly in side elevation and partly in central longitudinal section, of a modified form of pumping apparatus embodying my improvements.

Referring first to Figs. 1 to 4, which show the preferred form of the apparatus, A indicates a casing, which is of general cylindrical form reduced at opposite ends *a*, where it is screw-threaded to receive caps B B', which may be removed, when desired, the joints between the caps and the casing being packed, if necessary. Centrally arranged within the casing is a stationary guide-cylinder C. This is of much smaller diameter than the interior of the casing A, and it is shorter longitudinally than said casing.

The annular space between the guide-cylinder C and the interior of the casing A is divided longitudinally by a partition D into two chambers X and Y, which may be of equal area, one being used as a chamber for receiving the air before its delivery to the piston, while the other receives the air delivered by the piston. These chambers are connected with suitable exhaust and admission ports, hereinafter described. One of the chambers—the chamber Y as shown in the drawings—is closed at opposite ends by partitions *x* and *y*, while the other chamber, X, is open at opposite ends. The guide-cylinder C extends from one partition, *x*, to the other, *y*, and this cylinder opens at opposite ends into the chambers E and F at opposite ends of the casing A. Near each end, inside the corresponding partition *x* or *y*, the guide-cylinder C is enlarged, as at *c c'*. These enlargements are for the most part closed; but they are provided with openings C' C'', of large area and both communicating with the chamber Y. At each end the cylinder C, where it extends past the partitions *x* and *y*, is formed with a flange *f* to receive a packing-ring *f'*, which may be made of metal. The cylinder at each end is also screw-threaded at *f''* to receive a metallic screw-threaded ring G. A ring *f''*, of rubber, leather, or similar material, is interposed

between the ring G and the ring f' . These three rings G f' f^3 are assembled, as shown, to form valve-seats.

Within the guide-cylinder C is an endwise-movable cylinder H, acting also as a guide for the piston-head I. The cylinder H is adapted to reciprocate in the guide-cylinder C, which latter is preferably provided with bearing-rings c^5 , located, preferably, just inside the enlargements $c'c'$ of the guide-cylinders. The cylinder H extends into the enlarged portions of the guide-cylinder, and it is provided with an annular enlargement h at each end, preferably made slightly conical or tapering and adapted to fit a corresponding surface on the corresponding valve-seat ring f' and also on the ring f^3 , interposed between the valve-seat ring G and the ring f' . The ring f^3 may be made of rubber, leather, or other similar material.

At the lower end of the cylinder H is located a valve J. This valve is adapted to fit a corresponding surface on the valve-ring G, and the valve is normally seated by a spring j , interposed between the valve and the cap B'. The valve may be guided by a stem j' , guided by a chamber j^2 on the cap B'. The valve is closed by the spring and is opened automatically during the downward movement of the piston. At the opposite end of the cylinder H is located a valve K. This valve is adapted to rise and fall on the piston-rod L. It may be closed by a spring or by gravity. This valve is preferably tapered and fits a corresponding seat on the corresponding valve-ring G. The piston-rod L is connected with an arm m on a crank-shaft M. The cylinder-valve H is connected by a rod N with a frame O, which is slotted at o for the passage of the shaft M, and it is provided at opposite ends with rollers o' , against which bears a cam O', secured to the shaft M, the arrangement being such that as the shaft M is rotated the cam also will be rotated and will act on the rollers o' to cause the frame O to rise and fall and correspondingly actuate the rod N, which in turn changes the position of the cylindrical valve H. The rod N preferably extends through a tubular sleeve or casing n and through suitable packing.

The air is admitted to the chamber Y through a port P, and it is discharged through either a port P' or a port P², depending on the position of the reversing-valves, herein-after described. It would be sufficient to merely provide a port P for the admission of air to the chamber Y and a single port for the exhaust of air therefrom, and the apparatus might be employed in this way to either compress air or to exhaust it. I prefer, however, to employ the reversing mechanism shown and will therefore proceed to describe it.

On the outside of the casing A is located another casing Q, which is provided with a port q , communicating with the port P and

with ports $q' q^2$, communicating with the ports P' and P², respectively. On its opposite side the casing Q is provided with couplings $q^3 q^4$, which connect with pipes for the admission or discharge of air. The casing is provided on its interior with a shell Q', formed with valve-seats. There is a valve-seat $q^5 q^{10}$ on each side of the port q , and there is a valve-seat q^6 between the port P' and the coupling q^4 , and also a valve-seat q^7 between the port P² and the coupling q^3 . Two valves R and R' are arranged within the shell, the valve R being arranged to seat either on the valve-seat q^{10} or the valve-seat q^6 , while the valve R' is adapted to seat either on the valve-seat q^5 or the valve-seat q^7 . The valves are connected by a valve-rod S, which extends through packing s in the top of the valve-casing and also extends into a guide s' in the lower end thereof. The valve-stem is connected with a pitman-rod S', which is secured at its upper end to a frame T, slotted at t to receive a shaft U, on which is secured a cam U', adapted to turn between rollers t' , carried by the frame T, the arrangement being such that when the shaft U is rotated the cam will be correspondingly rotated and will act on the rollers t' to raise and lower the frame and correspondingly raise and lower the valves R R' to shift their position. The shaft U has secured to it a large gear-wheel V, which gears with a small gear wheel or pinion v on the shaft M. The arrangement is such that a large number of revolutions of the shaft M are required before the shaft U is rotated or turned sufficiently to change the position of the valves R R'. When the mechanism is in the position shown in Fig. 2 of the drawings, air will enter through the coupling q^3 and pass through the opening P into the chamber Y, as indicated by the unbroken arrows. The air will fill the chamber Y, but cannot escape from the lower end thereof, as the valve-cylinder H closes this chamber at its lower end. The air therefore passes upward and over the top of the cylinder H and follows the piston I in its downward movement. The air contained in the cylinder H will be forced downward by the piston and will force open the valve J. It then passes this valve and thence flows into the chamber F and thence into the chamber X on the opposite side of the partition D to that shown in Fig. 2. From the chamber X the air flows in the manner indicated by the dotted arrows to the port P', and thence out through the coupling q^4 , as indicated. After the piston I has reached the limit of its downward movement the endwise-movable cylinder H is shifted so as to cause its upper end to be seated and its lower end to be removed from the lower valve-seat. As the piston I moves upward the air entering through the port P will pass into the cylinder H at its lower end and follow the piston upward. During this upward movement the air above the piston will be forced past the valve K into the

chamber X and will then pass out through the port P', as before. This operation is repeated continuously for either compressing or exhausting the air, and it may be uninterrupted, large volumes of air being passed through the apparatus at each stroke of the piston, which may be run at high speed. It may be desirable, however, to reverse the apparatus, so that for a time it will compress and for a time exhaust the air from the same source or receptacle. This is accomplished by the valve-reversing mechanism before described. The apparatus might be operated for, say, one hundred strokes to carry air through the coupling q^3 and compress it through the coupling q^4 , and then the valves R R' might be changed, so that the air would be drawn through the coupling q^4 and expelled through the coupling q^3 . This is accomplished automatically by the gearing shown in Fig. 1 and before described.

In Fig. 5 I have shown a slight modification. This figure shows no means for reversing the apparatus, and the mechanism is somewhat simplified. At each end of the apparatus there is a chamber W, the casings of which are closed and connected by an open framing W', provided with guides w for the endwise-movable cylinder W². This endwise-movable cylinder W² is connected with a rod N in a similar way to that described in connection with Figs. 1 and 2, and it is adapted to be raised and lowered, so as to cause its opposite ends to be alternately brought in contact with a corresponding valve-seat w². The chambers W each communicate with a pipe W³, connected with a common delivery-pipe W⁴. There is a valve W⁵, similar to the valve J, between the lower chamber W and the open-work frame, and there is a valve W⁶ between the upper chamber W and the frame. The piston-head W⁷ is adapted to reciprocate in the cylindrical valve W² and may be operated in the manner illustrated in Fig. 1. In operation the air always enters through the open-work frame and passes into the valve-cylinder and thence into one of the chambers W, from which latter it is delivered through the pipe W⁴. In the position shown in the drawings the piston is moving upward, and air enters at the lower end of the valve-cylinder W², as indicated by the arrow, while the air above the piston is forced past the upper valve into the upper chamber and out through the pipe W⁴. When the piston W⁷ is ready to move downward, the cylindrical valve W² is first lowered and seated, and then the air enters from the outside over the top of the cylindrical valve, while the air in the cylinder is forced past the valve W⁵ into the lower chamber W, and thence out through the pipe W⁴.

The apparatus shown in Fig. 5 is similar to that shown in Fig. 2, in that chambers at opposite ends of the apparatus are alternately placed in communication with the cylindrical

valve, which is alternately shifted at each stroke of the piston for this purpose.

I claim as my invention—

1. The combination with a frame or casing having a chamber at each end formed by internal flanges, a cylinder-guide extending between such flanges and formed with an enlarged chamber adjacent each such flange and provided at its open ends with internal and external valve-seats, of an endwise-movable cylinder entirely open at its ends which extend into said enlarged chambers and is formed with a valve at each end adapted to seat against said internal valve-seats, automatically-acting valves seating against said external valve-seats, a piston reciprocating in said cylinder, its piston-rod passing through one of said automatically-acting valves and ports and passages for admission and expulsion of air.

2. The combination with a frame or casing having a chamber at each end formed by internal flanges, a cylinder-guide extending between such flanges and formed with an enlarged chamber adjacent each such flange and provided at its open ends with internal and external valve-seats, of an endwise-movable cylinder entirely open at its ends which extend into said enlarged chambers and is formed with a valve at each end adapted to seat against said internal valve-seats, automatically-acting valves seating against said external valve-seats, a piston reciprocating in said cylinder, its piston-rod passing through one of said automatically-acting valves, partitions which divide the annular space between the casing and cylinder-guide into two chambers, and ports and passages for admission and expulsion of air.

3. The combination with a casing having end chambers formed by internal flanges, a cylinder-guide extending between such flanges and open at both ends and at its ends formed with valve-seats, of automatically-acting valves tending normally to close the ends of the cylinder-guide, an endwise-movable cylinder reciprocating in said guide, the piston working therein, and inlet and outlet ports and passages.

4. The combination with a casing having end chambers formed by internal flanges, a cylinder-guide extending between such flanges and open at both ends and at its ends formed with valve-seats, of automatically-acting valves tending normally to close the ends of the cylinder-guide, an endwise-movable cylinder reciprocating in said guide, the piston working therein, the annular space between the casing and cylinder-guide being divided by partitions into two chambers, and inlet and outlet ports and passages.

5. The combination of a casing provided with a reception-chamber and a delivery-chamber, a cylindrical valve within the casing, a piston working therein, valve-seats for the opposite ends of the cylindrical valve, means for

shifting the position of the cylindrical valve, automatic valves at opposite ends of the cylindrical valve, a valve-casing outside the main casing, having two ports communicating with the delivery-chamber and another port communicating with the reception-chamber, valves governing these ports, and means for changing the position of the valves to cause

the fluid to enter through one or the other of the ports to the reception-chamber.

In testimony whereof I have hereunto subscribed my name.

BYRON B. BOWER.
